UNITED STATES PATENT OFFICE.

JACOB W. OGDEN, OF STAMFORD, CONNECTICUT, ASSIGNOR, BY MESNE ASSIGNMENTS, TO UNIVERSAL STAMPING MACHINE COMPANY, OF STAMFORD, CONNECTICUT, A CORPORATION OF DELAWARE.

FEED MECHANISM FOR MACHINES FOR MARKING MAIL, &c.

1,381,589.

Specification of Letters Patent. Patented June 14, 1921.

Application filed October 10, 1918. Serial No. 257,604.

To all whom it may concern:

Be it known that I, JACOB W. OGDEN, a citizen of the United States, residing at Stamford, in the county of Fairfield and State of Connecticut, have invented certain new and useful Improvements in Feed Mechanism for Machines for Marking Mail, &c.; and I hereby declare that the following is a full, clear, and exact description thereof, reference being had to the accompanying drawings, which form part of this specification.

This invention is an improvement in mechanism for feeding letters, checks, and like articles, to machines for operating thereupon; such as postmarking and canceling machines, and other mechanisms operating upon small articles of like nature. In particular the invention is an improvement in the feed mechanism of mail marking machines of the kind shown in Patent No. 1,022,191 of April 2, 1912.

The objects of the present invention are to enhance the accuracy of operation of the feeding mechanism; to provide means whereby the separator roller will be always substantially journaled and supported relatively to the feeding roller; to reduce the number of possible points of wear in the parts supporting said roller; to enable the yielding article guide to be adjusted relatively to the separator roller without disturbing the adjustment of the separator roller relative to the feed roller; to simplify the construction of parts; to prolong the maintenance of accurate adjustment of parts; and to reduce the liability of wear affecting the operation and position of such parts.

I will explain the invention with reference to the accompanying drawings in which—

Figure 1 is a plan view of part of a mail marking machine of the character shown in the aforesaid patent, with one embodiment of my invention incorporated in the feed mechanism thereof.

Fig. 2 is a detail side view of the yielding guide and reverse roller support with such parts mounted thereon.

Fig. 3 is a top plan view of the support detached.

Fig. 4 is a side view of said support.

Figs. 5 and 6 are top and rear views of the adjustable yielding guide detached.

Fig. 7 is a vertical section on the line 7—7, 55 Fig. 1.

Fig. 8 is a sectional detail.

In the machine indicated in said drawings, and as described in the aforesaid patent, the mail or other matter to be operated upon is placed on a feed table or belt 10 and advanced facewise against a stationary guide 11 and edgewise toward an inclined guide 8, by which the letters or articles are successively directed endwise against a preliminary feed roller 13 which feeds them to and between a second feed roller 14 and a yielding guide 9 (the latter improved as herein-after explained). A reversely rotating separator roller 15 is arranged opposite feed roller 14 and permits only one letter or article to be fed forward at a time by roller 14.

From the feed roller 14 each letter or article passes to and between a pair of feed rollers 16 and 17 which feed it onward and, 75 while in the bite of said rollers, the leading edge of the article strikes the end of a trip-finger 2 (that projects into an annular groove in roller 17) and rocks said finger as the article is advanced by rollers 16 and 17, 80 thereby releasing the marking roller or die 19 as described in the aforesaid patent. The letter or article fed forward by rollers 16 and 17 passes between an impression roller 18 and an opposed intermittently rotated die 85 or marking roller 19, which latter is adapted to be operated by mechanism controlled by the trip-finger 2 and receives ink from a roller 25 as described in said patent. Then the printed article passes between a pair of delivery rollers 20 and 21 to a suitable receiver or stacking device not shown. All of the aforesaid parts except as herein-after noted, may be arranged and adapted to operate substantially as described in the 90 aforesaid patent, and therefore are not further described herein.

In the present invention the separator roller 15 and so-called yieldable guide 9 are both mounted, as hereinafter described, upon 100 a swingable support A. Said support may be cast and is preferably bifurcated at one end, as shown in Figs. 2 and 3, to embrace the roller 17; the ends of the bifurcations being loosely but snugly fitted on the shaft 105 7 of the roller 17, above and below said roller, so that said support can swing horizontally on said shaft as its pivot.

As shown the support A has a lateral shank portion A' which is provided with a preferably integral vertical bearing A² in which the shaft 15^a of the separator roller 15 is journaled. The lower end of shaft 15^a may be connected by a universal joint 15^b to an actuating spindle 44 operated substantially as described in the aforesaid patent.

To the support A is suitably connected one end of a rod a, the other end of which extends through a sleeve b that is threaded through a stud c attached to the bed or table of the machine adjacent the swinging support A. The outer end of the rod a has a head f which bears against the outer end of the sleeve b and limits the inward movement of the support. A coil spring d is interposed between the inner end of this sleeve and a collar e adjustably secured on the rod a; said spring acting to press the support A yieldingly toward the feed roller 14. The normal distance between the periphery of the feed roller 14 and separator roller 15 is regulated by adjusting the sleeve b. The adjusting rod a may be pivoted to support A by a shouldered screw M which acts as a pivot for the rod.

In the present invention the yielding guide 9 instead of being formed integral 30 with its support, as heretofore, is adjustably mounted on the support A; and for this purpose said support is provided with adjacent, horizontal, parallel bores D and C (Figs. 3 and 4) which are adapted to be respectively engaged by pins 9^a and 9^b attached to the guide plate 9. The outer end of the pin 9^b is threaded and engaged by a rotatable nut H. The pins 9^a and 9^b may be riveted to guide 9, and the latter reinforced 40 adjacent such points by a plate E. Said guide 9 has a slot 9^c in it through which one side of the separator roller 15 projects when the parts are properly assembled and adjusted.

Preferably the outer end of the bore C in the support is enlarged to receive the hub h of the knurled nut H, and two small holes 5 are drilled in the support, intersecting said enlarged part of the bore, to receive a steel 50 wire staple G which engages the annular groove h' in the hub of the nut H and holds it rotatably in place in the support, and prevents endwise movement thereof.

A hardened steel ball I and spring K may 55 be placed in a hole 6 in the support so arranged that the ball will engage one of a series of depressions in the inner face of the nut H and prevent it from turning too freely, while permitting it to be turned to 60 adjust the yielding guide 9 on the support.

The guide 9 is assembled with the support A by placing the pins 9^a and 9^b in the holes C and D and engaging nut H with the threaded part of pin 9^b. By turning the 65 nut H the guide 9 can be adjusted to the

required position relative to the separator roller 15.

It is quite important in machines of this type that the reverse separator roller 15 should run smoothly and accurately relatively to the feed roller 14 to insure that the letters or articles being fed are properly separated, and to prevent jumping thereof, or irregularities in the separation of the letters.

The position of the separator roller 15 relative to the feed roller 14 is controlled and can be accurately adjusted by turning the sleeve b; and the position of the guide 9 can be further adjusted independently of the adjustment of the support A and roller 15, by turning the nut H.

The guide 9 yields or moves with the swingable support A the same as if it were rigidly attached thereto, but it can be adjusted relatively to the roller 14 independently of roller 15 to compensate for wear of the periphery of the separator roller 15.

The only points of possible wear in this novel construction are the journal bearing 90 of the spindle of the separator roller 15 in the support A; and the pivot bearings of said support upon the shaft of the roller 17. As each of these bearings is comparatively large very little wear develops.

As compared with the devices heretofore used the present construction is more compact, much simpler, has less points of wear and the parts are more conveniently adjustable.

What I claim is:

1. In a machine of the character specified, the combination of a feed roller, an adjacent pair of feed rollers, a swingable support pivoted on the shaft of one of the pair of feed rollers and extending opposite the first feed roller, said support having a vertical bearing for the spindle of a separator roller, a separator roller having its spindle journaled in said bearing, and an adjustable guide 105 plate on said support.

2. In a machine of the character specified, the combination of a feed roller, an adjacent pair of feed rollers, a swingable support pivoted on the shaft of one of the pair of feed rollers and extending opposite the first feed roller, said support having a transverse bore; a separator roller mounted on said support, a guide plate having a pin engaging the said bore, means for adjusting said guide 110 on said support, and means for adjusting and yieldingly holding the support in adjusted position.

3. In a machine of the character specified, the combination of a feed roller, an adjacent pair of feed rollers, a swingable support pivoted on the shaft of one of the pair of feed rollers and extending opposite the first feed roller, said support having a vertical bearing for the spindle of a separator roller and 125

- 5 a transverse bore; a separator roller having its spindle journaled in said bearing, an adjustable guide plate having a pin engaging the said bore, and means for adjusting said support and yieldingly holding the same in adjusted position.
4. In a machine of the character specified, the combination of a feed roller, an adjacent pair of feed rollers, a swingable support pivoted on the shaft of one of the pair of feed rollers and extending opposite the first feed roller, said support having a vertical bearing for the spindle of a separator roller and transverse bores; a separator roller having its spindle journaled in said bearing, a guide plate provided with pins engaging the said bores, means for adjusting said guide on said support, and means for adjusting said support and yieldingly holding the same in adjusted position.
- 10 5. In a machine of the character specified, the combination of a feed roller, a swingable support opposite the feed roller having a vertical bearing for a separator roller and
- 15 20 25 a transverse bore, a separator roller journaled in said bearing, a guide plate provided
- with a threaded pin engaging the said bore; a nut rotatably confined to the casting and engaging the threaded end of said pin for adjusting said guide on said support; and an adjustable spring pressed rod pivotally connected with said support and yieldingly holding the same in position.
6. In a machine of the character specified, the combination of a feed roller, an adjacent pair of feed rollers, a swingable support pivoted on the shaft of one of the pair of feed rollers and extending opposite the first feed roller, said support having a vertical bearing for a separator roller and transverse bores; a separator roller having its spindle journaled in said bearing, a guide plate provided with pins engaging the said bores, a nut rotatably confined to the casting and engaging the threaded end of one of said pins for adjusting said guide on said support; and an adjustable spring pressed rod pivotally connected with said support and yieldingly holding the same in position.

In testimony that I claim the foregoing as my own, I affix my signature.

JACOB W. OGDEN.
